(57) **CLAIM**

The ornamental design for a cup holder, as shown and described.

DESCRIPTION

FIG. 1 is a first perspective view of a cup holder;
FIG. 2 is a side view of the cup holder of FIG. 1, with all other sides being identical;

FIG. 3 is a top view of the cup holder of FIG. 1;
FIG. 4 is a bottom view of the cup holder of FIG. 1;
FIG. 5 is a second perspective view of the cup holder of FIG. 1;

FIG. 6 is a third perspective view of the cup holder of FIG. 1; and,

FIG. 7 is a fourth perspective view of the cup holder of FIG. 1.

Any components in the appended drawings shown in broken lines are for illustrative purposes only and form no part of the claimed design.

1 Claim, 7 Drawing Sheets
